(57) **CLAIM**

The ornamental design for a portion of a display panel with an animated computer icon, substantially as shown and described.

DESCRIPTION

FIG. 1 is a front view of a first embodiment of a first image in a sequence for a portion of a display panel with an animated computer icon, showing my new design.

FIG. 2 is a front view of the second image in the sequence thereof.

FIG. 3 is a front view of the third image in the sequence thereof.

FIG. 4 is a front view of the fourth image in the sequence thereof.

FIG. 5 is a front view of the fifth image in the sequence thereof.

FIG. 6 is a front view of second embodiment of a first image in a sequence for a portion of the display panel with an animated computer icon, showing my new design.

FIG. 7 is a front view of the second image in the sequence thereof.

FIG. 8 is a front view of the third image in the sequence thereof.

FIG. 9 is a front view of the fourth image in the sequence thereof; and,

FIG. 10 is a front view of the fifth image in the sequence thereof.

The appearance of the transitional image sequentially transitions between the images shown in FIGS. 1-5 and FIGS. 6-10. The process or period, in which one image transitions to another image, forms no part of the claimed design.

The broken lines showing a portion of a display panel and portions of the animated computer icon in FIGS. 1-10 form no part of the claimed design. The outermost solid lines in FIGS. 1-10 represent a portion of the display panel, which forms a part of the claimed design.
